UNITED STATES PATENT OFFICE

2,234,045

OPENER FOR PLASTIC BINDINGS

Charles Edward Emmer, Chicago, Ill., assignor to
 General Binding Corporation, Chicago, Ill., a
 corporation of Illinois

Application September 8, 1939, Serial No. 293,878

7 Claims. (Cl. 11—1)

During recent years, an increasingly large number of catalogs, sales presentation pieces, magazines of the better class, and other forms of books have been bound by what are known as 5 mechanical bindings, that is, bindings which comprise a series of rings extending loosely through holes along the edges of the pages at the back of the book.

One class of mechanical bindings which has 10 been proven to be quite practical and popular is that known as "plastic bindings" which are formed from sheet Celluloid or similar plastic such as Cellulose acetate.

One practical form of plastic binding is shown 15 in the U. S. Patent to Douvry No. 1,970,285 entitled "Binding arrangement" and dated August 14, 1934, and another, with some modifications thereof, is shown in my copending patent application No. 227,242 entitled "Plastic binding" 20 and filed on August 29, 1938.

Plastic bindings are used largely for binding publications of limited circulation which are often printed locally in small establishments. Thus, while the binding itself may be made in 25 a factory with relatively expensive production machinery, the actual application of the binding to the book is often done in a small shop which does not do enough of such work to warrant the purchase of a special machine for that purpose. It is therefore desirable to provide a small inexpensive hand tool for rapidly and economically applying plastic binding and the like to pages 30 to be bound by the binding. The principal object of this invention is to provide such a tool. Another object of this invention is to provide 35 an opener for plastic bindings and the like, whose operation will be independent of the spacing of the rings of the binding so that the same device may be used with bindings having their rings spaced differently.

In order to accomplish these and other objects, I have provided a device whose principal feature is a bayonet or blade of special shape which is adapted to be inserted endwise through 45 the rings of the binding and, when so inserted, spreads the rings open so as to form a gap into which the pages to be bound can be inserted. Then, when the bayonet or blade is withdrawn, it allows the rings of the binding to close through 50 the holes in the edges of the pages and thus secure the pages together.

My invention itself, however, both as to its organization and manner of construction, together with further objects and advantages thereof, may 55 best be understood by reference to the following

description of some of its practical embodiments, and by reference to the accompanying drawing, in which:

Figure 1 is a plan view of one of the preferred forms of my invention;

Figure 2 is a side elevation of the form of the invention shown in Figure 1;

Figure 3 is a section, on an enlarged scale, of a group of pages being secured together with a binding being applied with the device shown 10 in Figures 1 and 2;

Figure 4 is a side view of the process illustrated in Figure 3;

Figure 5 is a cross section taken on the line V—V of Figure 3 and looking in the direction 15 of the arrows;

Figure 6 is a cross section taken on the line VI—VI of Figure 3 and looking in the direction of the arrows;

Figure 7 is a cross section on the line VII—VII 20 of Figure 3 and looking in the direction of the arrows;

Figure 8 is a cross section of a modified form of the invention; and

Figure 9 is a side view of another modified 25 form of the invention.

The form of the invention illustrated in Figures 1 to 7 comprises a straight blade or bayonet 11, preferably made of smooth metal and having narrow upstanding flanges 12 and 13 along each 30 side. The main part of the blade 11, therefore, is channel-shaped in cross section, as shown in Figure 7. The base or root end of the blade 11 is provided with a tang 14 projecting down at approximately right angles to the main part of 35 the blade and secured in a handle 15.

The end of the blade away from the handle 15 is cut obliquely, as shown in Figure 1, to form a rounded point 16 which is located eccentrically of the blade and approximately in line with the 40 flange 13 along one edge of the blade. The entire blade or bayonet 11, and particularly the sloping edge 17 extending back from the point 16, is smooth and polished so that it will slide with the minimum of friction through a binding 45 being opened.

The particular form of the invention shown in Figures 1 and 2 is especially adapted to be used in connection with plastic bindings of the type shown in my above mentioned copending 50 application. As shown in Figures 3 to 7, this form of binding comprises a longitudinally extending backbone 21 from one edge of which extends a plurality of fingers 22, 23, 24, 25 which are curled around upon themselves to form rings. 55

The binding 21-25 is made of some material such as cellulose acetate which is resilient enough to permit the rings 22, 23, 24 and 25 to be sprung open for the insertion of the pages 26. Each 5 page is provided with a series of holes 27 through which the rings 22, 23, 24 and 25 of the binding are to extend in order to hold the pages together and to permit them to be moved relative to each other.

10 The binding 21-25 is opened up for the insertion of its rings 22, 23, 24 and 25 into the holes 27 of the pages 26 as follows: The point 16 of the opener is inserted into the end ring 25 of the binding, care being taken to see that the binding and the opener are held relative to each other so that the backbone 21 of the binding is on the concave side of the blade or bayonet 11 and that the ring 25 extends from the backbone 21 past the long straight edge or flange 13 of the blade 11 and then around the other edge of the blade and not in the opposite direction. The blade 11 of the opening is then pushed all the way into the binding 21-25, whereupon each of the rings 22, 23, 24 and 25 will be spread open by the 15 oblique edge 17 extending back from the point 16 of the blade 11 and will be held open by the parallel main portion of the blade.

20 The position of each ring as the point 16 of the blade or bayonet enters it is illustrated by the ring 23 in Figures 3, 4, and 5, although these figures illustrate a later stage of the process when the pages 26 are in place. As the blade 11 enters each ring, the position of the ring relative to the blade is illustrated by the ring 24 25 in Figures 3, 4, and 6, and the oblique edge 17 of the end of the blade forces the ring open. When the body of the blade is forced into each 30 ring, the position of the ring relative to the blade is illustrated by the ring 25 in Figures 3, 4, and 7, and it will be seen that the ring has now been 35 sprung open far enough to allow the pages 26 to be inserted.

30 When the blade 11 has been forced far enough into the binding 21-25 to cause all of the rings 45 22, 23, 24, and 25 to be held open by the parallel-sided main portion of the blade 11, the perforated edges of the group of pages 26 are placed between the flanges 12 and 13 on the blade of the opener with the perforations 27 aligned with 50 the rings 22, 23, 24, and 25, and the blade is withdrawn from the binding. During this operation the pages 26 and the binding 21-25 are held stationary with respect to each other so that, as the blade 11 is withdrawn, each of the rings 55 22, 23, 24, and 25 closes up upon itself.

55 As the rings close up, they thread themselves through the holes 27 in the pages 26, this process being illustrated by the rings 25, 24, and 23 which are shown in the drawing as being in 60 successive stages of that process. As may be seen from Figure 5, this process leaves the rings closed up upon themselves and threaded through the holes 27 in the pages 26, which binds together the pages 26 in the desired relationship.

65 In Figures 3 to 7, the binding of comparatively small pages, such as might comprise a memorandum book, has been illustrated, but the opener shown in these figures may also be used for the binding of larger pages. When larger pages are 70 to be bound, they are provided with groups of perforations, similar to the perforations 27 in the pages 26, along one edge, each group comprising, for example, four perforations and there being two or three groups spaced from each 75 other. Then one binding, similar to the binding

21-25 illustrated in Figures 3 to 7, and having the same number of rings or fingers as there are perforations in each group of perforations is placed in each of said groups of perforations. There will thus be as many binding elements as 5 there are groups of perforations and each one will be placed in position in a distinct operation. It will be readily seen that in carrying out 10 at least one of these operations, the edges of the pages being bound will extend past the handle end 15 of the opener with which the operation is being carried out. Because of this, the trough whose two sides are defined by the flanges 12 and 13 on the blade 11 is unobstructed at any point and the handle 15 and its attached means 14 are so constructed as to lie entirely out of line with that trough. This permits the device to be readily used for applying a binding at any point along 15 the edges of a group of pages.

20 While the form of the device illustrated in Figures 1 to 7 and described above seems, at the present time, to be the most convenient, the device may take other forms. For example, the blade of the device, instead of having a simple channel shaped cross section may be as illustrated 25 in Figure 8 which shows a blade 31 having a longitudinal groove 32 along one edge, the groove 32 being adapted to receive the backbone 21 of the binding shown in Figures 3 to 7. When a binding is opened with the form of the device shown in Figure 8, the only portions of the binding projecting above the blade 31 of the device are the ends of the rings which are to be inserted 30 in the perforations of the pages to be bound, and this may facilitate the lining up of the pages 35 with the rings.

Another form of the device is illustrated in Figure 9. In this form of the device, the blade 35, which may be of the same type as in the device illustrated in Figures 1 to 7 or of the type illustrated in Figure 8, is two or three times as long 40 so as to be able to accommodate single bindings long enough to bind large pages with a single long binding element. The handle 38 is located approximately opposite the middle of the blade 45 35 and is fixed on a tang 37 at the end of a gooseneck 36 extending around from the butt end of the blade.

50 While I have described my invention as being used in connection with plastic bindings of the particular type shown in my above mentioned co-pending application, it will be obvious that the device may be designed to be used with other types of bindings. In fact, the particular device shown in Figures 1 and 2 operates satisfactorily 55 on plastic bindings of the Douvry type although designed specifically for use upon the type of plastic binding shown by above mentioned application. It will also be apparent that opening devices of this type may be used in connection 60 with bindings of the general type described even though they may be made of other materials than plastic such as, for example, resilient metal.

65 From the above, it will be apparent that I have invented a simple device for opening plastic bindings and applying them to pages to be bound, and this device is extremely simple to operate and extremely inexpensive to manufacture.

70 While I have shown only three particular embodiments of my invention, it will of course, be understood that I do not wish to be limited thereto, since many other modifications may be made, and I therefore contemplate by the appended 75 claims to cover all such modifications as fall 75

within the true spirit and scope of my invention.

I claim as my invention:

5 1. An opener for binding elements of the type described comprising a smooth round-edged blade having a body portion of even width and a tapered end portion, one edge of said tapered end portion being in line with one edge of said body portion.

10 2. An opener for binding elements of the type described comprising a smooth round-edged blade having a channel-shaped body portion of even width, a tapered end portion, and a handle, said handle being secured to said body portion at the end thereof opposite said tapered end portion 15 and lying far enough to one side of said body portion so that no portion of said handle or of a hand grasping said handle lies in line with the channel in said channel portion, the channel side of said channel-shaped body portion being completely unobstructed.

20 3. An opener for binding elements of the type having a plurality of resilient fingers extending around from a longitudinal backbone and forming rings, which comprises a smooth edged blade 25 having a body portion of even width and edge portions curled partially back over the body portion, said width being substantially one and one-half times the diameter of said rings, and having a tapered end portion.

30 4. An opener for binding elements of the type described comprising a channel-shaped blade

having parallel flanges along each edge, one end of said blade having the form of an oblique point with one of said flanges extending substantially to the end of said point and the other of said flanges terminating at the beginning of said point. 5

5. An opener for binding elements of the type described comprising a smooth round-edged blade having a body portion of even width and a tapered end portion, said blade being provided with a handle substantially opposite the midpoint thereof and secured to the other end of said blade by a gooseneck. 10

6. An opener for binding elements of the type described comprising a smooth round-edged blade having a body portion of even width and 15 a tapered end portion, one edge of said blade being formed with a longitudinally extending groove.

7. An opener for binding elements of the type having a plurality of resilient fingers extending 20 around from a longitudinal backbone and forming rings encircling the backbone, which comprises a smooth round-edged blade having a body portion of even width and a tapered end portion, one edge of said tapered end portion being in 25 line with one edge of said body portion and said edge of said tapered end portion and said body portion being provided with a straight longitudinal groove for receiving said longitudinal backbone. 30

CHARLES EDWARD EMMER.
